UNITED STATES PATENT OFFICE

ARTHUR D. LUND, OF MINNEAPOLIS, MINNESOTA, ASSIGNOR TO ALCET ELECTRO-
PRODUCTS CORPORATION, OF NEW YORK, N. Y., A CORPORATION OF NEW YORK

GRID CASTING MACHINE

Application filed August 24, 1928. Serial No. 301,830.

This invention relates to machines for casting articles from molten metal, and the main object is to provide a highly novel, efficient and practical machine particularly designed and adapted for the purpose of casting grids for batteries. Further and more specific objects are to provide, in such a machine, an improved construction of grid forming molds, improved means for automatically opening and closing the molds, improved means for mounting and cooling the molds, improved means for smoking or treating the molds prior to filling, improved means for melting and systematically delivering the molten lead in predetermined charges to the molds, and improved means for receiving the completed grids from the molds and delivering them to a point remote therefrom. These and other objects will be more specifically enumerated and set forth in detail in the following specification, reference being had to the accompanying drawings, in which:

Fig. 1 is a side elevation of the machine, as seen from its right side, the right end of the view being considered as the front of the machine, fractional portions being broken away for purpose of illustration.

Fig. 2 is a plan view of the machine with fractional portions broken away or removed.

Fig. 3 is an enlarged sectional elevation, as on the line 3—3 in Fig. 1.

Fig. 4 is an enlarged sectional elevation on the line 4—4 in Fig. 1.

Fig. 5 is a front elevation of the machine with fractional portions broken away.

Fig. 6 is a side elevation of the lower portion of the machine, as seen from its left side.

Fig. 7 is a sectional plan view as seen substantially on the irregular line 7—7 in Fig. 6.

Fig. 8 is a detail sectional elevation as taken approximately on the line 8—8 in Fig. 3.

Fig. 9 is an enlarged sectional elevation on the line 9—9 in Fig. 2.

Fig. 10 is a side elevation of the melting unit showing the metal pumping or feed mechanism in a raised position.

Fig. 11 is a detail plan view of the metal feed spout and pump chamber.

Fig. 12 is a detail section as on the line 12—12 in Fig. 11.

Fig. 13 is a sectional detail view of the feed nozzle, which is superimposed upon the spout shown below in Fig. 12.

Fig. 14 is a detail elevation, partly in section, showing the pump unit and piston actuating mechanism. 55

Fig. 15 is an enlarged detail plan view of the lever mechanism shown in Fig. 14.

Fig. 16 is a detail side elevation of the device shown in Fig. 15, with a fractional portion sectioned away. 60

Fig. 17 is an end view of the device as seen from the right in Fig. 15.

Fig. 18 is a detail elevation, partly in section, as on the line 18—18 in Fig. 19, of the metal control valve and operating mechanism 65 therefor.

Fig. 19 is a detail view, partly in section, as on the line 19—19 in Fig. 18.

Fig. 20 is a detail plan view of one of the pump actuating connecting rods. 70

Fig. 21 is a detail elevation of the rod shown in Fig. 20, with a portion thereof shown in section, as on the line 21—21.

Fig. 22 is a section on the line 22—22 in 75 Fig. 21.

Figs. 23, 24 and 25 are views similar to Figs. 20, 21 and 22, but of the valve actuating rod.

Fig. 26 is a plan view of the smoking unit, 80 fractional portions being broken away.

Fig. 27 is a right end view of the smoking device, partly in section as on the line 27—27 in Fig. 26.

Fig. 28 is a detail section, as on the line 85 28—28 in Fig. 26, but showing the burner carrier as locked in its idle position.

Fig. 29 is a plan elevation of one of the pairs of molds or die units, the left half of the near mold being broken away. 90

Fig. 30 is a top view of the device shown in Fig. 29, but with the left halves of both units shown in section.

Fig. 31 is an enlarged detail sectional view as on the line 31—31 in Fig. 3. 95

The smelter or melting mechanism of the machine consists of a base member 34, mounted on four legs 35, and having a pair of side frame members or standards 36, between which is mounted a furnace box 37. 100

having a brick lining 38. The lead pot 39 has an annular flange 40 resting upon the box 37, so as to confine the space between the two, which space is heated by gas burners 41 fed by a gas pipe 42. The box 37 is provided with a door 43 for cleanout purposes and through which the height of the flames may be observed. The gas and fumes are permitted to escape through side ports 44 to connected smoke pipes 45. The lead pot 39 is provided with a pair of laterally disposed slides 46 upon which the lead ingots may be placed, and from which they may be pushed into the pot as the metal level lowers.

The lead feeding or pumping devices, of which two are employed in the present machine, are carried on a cross frame 47, pivotally secured as at 48 to the standards 36, and which frame may be tilted up, so as to lift the pumps out of the metal, through the medium of a hand crank 49, shaft 50, bevel pinions 51 and vertical, threaded shafts 52 operating in arbors 53 of the frame 47. When in its lowered, operative position the frame 47 is securely held down by a releasable bolt 54. The feed mechanism is shown in its raised position in Fig. 10.

The machine here shown employs two sets of grid casting molds, and the molten lead is fed into these molds by two pumps. Each of these pumps comprises a chamber 55 at the lower end of a depending arm 56, secured to the frame 47, and a lead displacement piston or plunger 57 adapted to move up and down in the chamber. The downstroke of the piston forces a predetermined amount of lead from the chamber out through a spout 58, and through a nozzle 59 into the mold. Upon the up stroke of the piston a valve 60 is opened permitting the chamber 55 to again fill up, it being understood that the level of the metal in the pot 39 is always above the valve ports 60. It will be noted that the normal lead level in the pot 39 is also above the spout 58, with a result that there is no tendency to cool the lead in the spout until it is injected into the molds, as would be the case if the spout were exposed to the atmosphere. The lead level with respect to the pump 55-57 is indicated in Figs. 5, 8 and 14, and it is of considerable importance that it is so located, for reasons that will presently appear. The piston 57 operates through a packing gland sleeve 61, secured as at 62, and through a smaller sleeve 63 screwing into the sleeve 61. The openings in these sleeves are sufficiently large to freely receive the plunger 57, and preferably do not contact with it at all, their sole object being to hold a packing composition, as at 64, and to hold a lubricant, such as powdered graphite, as at 65. A heavy bearing member 66 forms the primary bearing support and guide for the plunger 57. The material 64 is of course tightly packed about the plunger by screwing down

of the sleeve 63, and its sole purpose is to keep air out of the pump chamber and also to wipe the lead off of the rising piston. By this construction, it will be noted, all possibility of litharge forming on the piston is entirely eliminated, as no part of the piston contacting with the lead comes in contact with the atmosphere, at least until it is first entirely wiped clean.

The pistons 57 are connected, at their upper ends, by links 67, to the front ends of bent levers 68, fulcrumed, as at 69 to the frame 47, the rear ends of which levers 68 are connected by links 70 to arms 71 of a sleeve 72 having a single actuating arm 73 (see Figs. 15-17), the sleeve 72 being trunnioned on a shaft 74 carried by the frame 47. The links 70 are connected to the arms 71 by pivot studs 75 adjustably secured on screws or worms 76 of the arms 71. Thus, by turning these screws, the operating radii of the links 70 may be independently adjusted with reference to the shaft 74, and consequently the strokes of the pistons 57 may be independently adjusted with reference to each other and with respect to the stroke of the member 71-73. The arms 68 are both provided with lugs 77 connected by lift rods 78 and compressed expansion springs 79 (see Figs. 4, 10, 14) the objects of which are to counterbalance the weight of the pistons 57 and to take up slack or play in the various joints and link connections above described.

Slidably secured upon the arm 73 of the sleeve 72 is a bearing block 80 the longitudinal position of which on the arm is governed by a screw shaft 81 that is journaled in a bearing portion 72a (Figs. 15, 16) of the sleeve 72, and which shaft has a knurled adjustable head member 82 by which the bolt is turned to move the block 80 in or out. A spring held pin 83 operates to frictionally engage detents on the member 82 to keep the bolt from accidentally turning. The block 80 is connected to the upper forward end of a bar 84 which has a uniform oscillating or reciprocating action but by turning the bolt 81 it will be seen that its radius will be changed and consequently a shorter or longer stroke to both pistons 57 can be equally and simultaneously effected. It may be noted that when the bar 84 moves in a forward direction, i. e., to the right as in Fig. 14, the pistons 57 will rise in the chambers 55, and, upon a reverse movement of the bar 84 the pistons will descend into the chambers displacing a certain amount of metal that is then fed rearwardly and into the molds.

The lower or rear end of the bar 84 is connected to the upper end of a lever 85, fulcrumed as at 86 in a housing 87, and having a lower arm which carries a roller 88 that in turn travels in a cam groove or channel 89 of a cam rotating cam plate or disk 90. It

will be noted, with particular reference to Fig. 14, that as the cam plate 90 rotates, with a uniform motion in the clockwise direction, indicated by the arrow, the roller is thrust forward during the relatively short travel of the cam groove from points A to B, which travel imparts the down or feeding stroke to the pistons 57. As soon as the feed stroke is completed the cam immediately drops back a very short distance, as at the point C, thus causing a slight retraction of the pistons. This retraction is effected before the valves 60 are opened, the object being to pull the lead in the spout 58 (see Fig. 8) back enough to prevent any of the metal to drip over and down through the nozzle 59. From the points C to D there is a relatively slight action to the roller 88 and the pistons 57 are raised quite slowly but during this movement the valves 60 are opened so that new charges of metal may be drawn or flow into the pump chambers 55. The pumps are substantially idle while the cam plate 90 travels from D to A this interval being required for forming and discharging the grid plates prior to the making of succeeding plates.

As shown particularly in Figs. 20-22, the rod 84 is formed of two telescoping sections, one, 91, of which is a forked socket member that connects directly to the block 80. The member 91 contains a friction pawl 92 held in engagement with a notch in the bar 84 under the pressure of a spring 93, the tension of which may be adjusted by a threaded plug 94. A pin 95 extends up from the pawl 92 and has a cam hand lever 96 by which the pawl may be manually released from the bar 84 when so desired. The occasion for so disconnecting the bar arises particularly when the pumping mechanism is to be lifted out of the metal pot, as shown in Fig. 10. It will be noted, however, that the pawl tooth inclines in both directions (Fig. 21) with a result that an undue strain between the parts 84 and 91 will cause a disengagement of the pawl. This is to provide against breakage of parts as would happen for instance if the power were applied after the lead in the pot or pump chambers had cooled or hardened beyond its workable consistency.

The lead chamber valves 60 are opened and closed by the vertical reciprocating action of a pair of rods 97, guiding, as at 98, at their lower ends, and in bearings 99 near their upper ends (Fig. 18). Springs 100, the tensions of which are regulated by adjustment nuts 101 tend to hold the rods 97 down with the valves closed. At their extreme upper ends the rods 97 are provided with collars 102 under which engage the bifurcated or fingered ends of the arm 103 of a lever which fulcrums as at 104 and has a rearwardly and upwardly projecting arm 105. This arm 105 is connected by a bar 106 to the upper arm 107 of a lever that fulcrums

as at 108 and has a lower arm 109 provided with a roller 110 that travels on the face of a cam 111. A spring 112, acting upon the arm 103 to pull it down tends to take all slack out of the joints and keeps the roller 110 in continuous working contact with the edge of the cam 111. The bar 106 is made telescopic in much the same manner and for the same reasons as previously described in connection with the bar 84. Thus, as shown in Figs. 23-25, the bar 106 is held in releasable engagement with a socket member 113 by a pawl 114 under the action of a spring 115 and subject to be manually disengaged under the action of a cam lever 116.

The cam 111 is preferably an integral flange portion of the hub section 117 of the cam plate member 90 (see Figs. 3 and 18). The hub section 117 is secured upon a sleeve 118 rotatably carried, by bushings 119 at its ends, upon a shaft 120 secured in the housing 87. The sleeve 118, as well as the various cam members carried by it, are rotated by a worm gear 121, carried by the sleeve within a casing 122, and which meshes with a worm 123, on a shaft 124 (see Figs. 2, 3, 7, 8), driven by a chain 125 (in housing 126), from a power unit or motor 127. A clutch 128 operatively connects the shaft with the motor, and includes a shipper fork 129 on a shaft 130, and a hand lever 131 for oscillating the shaft to throw the clutch into and out of engagement.

It is sometimes desirable to operate the machine very slowly, especially when observations and adjustments are to be made, and with this in view I provide the front end of the shaft 124 with a bevel pinion 132. A complementing bevel pinion 133 is slidably carried on the inner end of a shaft 134 which, at its outer end is connected by bevel pinions to a vertical shaft 135 having a hand crank 136. The pinion 133 is normally held out of engagement with the pinion 132 by a spring 137, but may be pressed into engagement therewith by a foot pedal 138 operating against a pinion position control rod 139. Thus it will be seen that by releasing the clutch 128, and then pressing the pedal lever 138 the power gear 121 may be rotated by the hand crank 136, and when the member 138 is again released the connection between the pinions 132 and 133 is disrupted. It may here be noted that the housing 87 is provided with a door 140, through which the various mechanisms within the housing may be cleaned, oiled, repaired, and adjusted.

In connection with the cam operation shown particularly in Fig. 18 it may be stated that the parts are so proportioned and arranged that the valve 60 remains open during the travel of the roller 110 on the cam surface extending from E to F, the valve closes from points F to G, remains closed until the roller reaches point H, and opens

on the stroke from H to E. And these movements are all timed and synchronized with reference to the pump actuating mechanism, with a result that the valves remain closed during the down stroke of the pump pistons and for a moment thereafter, to prevent dripping as above noted, and then opens and stays open during the major up stroke of the pistons, which is the chamber filling period, and this cycle is repeated for each casting operation.

Referring to Figs. 1 and 2 the numeral 141 designates a support for the bar 142 of a metal temperature indicator (not shown), and the numeral 143 designates brackets which support a partitioning plate 144 that extends down into the lead pot to hold back the lead ingots until they have become melted. It may here be noted that in the pump chambers 55 are provided valve controlled vents 145, through which the chambers may be drained when the feed mechanism is raised to the idle position shown in Fig. 10. It will also be noted (see Figs. 9, 10 and 13) that the upper end of the nozzle members 59 is covered by caps 146, held down by screws 147 of hinged U-brackets 148, and which when opened will permit the nozzles 59 and spouts 58 to be readily cleaned.

30 The mold operating mechanism, the mold treating mechanism, the mold mountings, the molds proper, and the grid conveying mechanism will now be described in detail.

Arranged between the housing 87 and the base 34-35, are a pair of heavy side frame castings 149, connected by a cross bar 150, and rigidly secured to the housing 87, as by bolts 151. Upon the members 149 is securely mounted a heavy cross beam 152 to which the stationary molds 153 are mounted. The movable molds 154 are carried by a pair of rams 155, slidably secured in races 156 on the housing 87. These rams are simultaneously actuated, and, as each pair of molds is designed to cast four grids in one plate, it will be seen that eight grids are cast or formed by each cycle of operation of the machine. The molds are shown in their closed or metal receiving positions in Figs. 8, 9, 10, 29 and 30, and Figs. 1 and 2 show the molds open or separated, at which periods the grids are discharged and the matrix faces of the molds are cleaned or smoked.

Each ram is actuated or reciprocated by the oscillating action of a lever 157, the upper end of which projects into the ram (Figs. 3 and 8), while its lower end is trunnioned on a fixed shaft 158 in the bottom of the housing 87. The upper end of the lever is provided with a pivoted block 159 that operates between a fixed abutment 160, secured by a bolt 161, and the head 162 of a slidable bolt 163. A heavy spring 164 is disposed between the nut 165 and a portion of the ram, and tends to hold the head 162 in firm contact with

the block 159. The tension of the spring 164 may be regulated by turning the nut 165, after a cover plate 166 is first removed. As the levers 157 oscillate back and forth they correspondingly reciprocate the mold carrying rams, the blocks 159 having sufficient freedom for the vertical sliding action between the members 160 and 162 occasioned by arc of travel that the block 159 must move in. The springs 164 permit the molds to stop, in their forward course, should the previously formed grids not be fully discharged or should any other object get between and prevent a full closing of the molds, in which case the comparatively delicate matrix surfaces should become seriously damaged.

70 The levers 157 each operate between a pair of cams 167, and have rollers 168 adapted to travel on the peripheries of these cams. The cams are secured on the sleeve 118, rotating therewith in a clockwise direction, as shown in Fig. 8. The major portions of the cam surfaces are circular, and as the rollers 168 travel on these portions extending from J to K, they are stationary, and in which positions they hold the levers 157 forward and the molds closed. The roller engaging surface from K to J is inwardly curved (Fig. 8) and is complemented by an outer, cam 80 edged member 169, which, as the point K approaches the roller, engages the roller and moves the lever 157 rearwardly thus opening the molds. It will thus be seen that the eight cam members 167, 169, 111, and 90 are 90 all mounted on and simultaneously rotated with the sleeve 118 by the motor 127.

95 The stationary molds 153 are secured to the beam 152 by bolts 170 having springs 171 which hold the molds firmly back against 100 adjusting set screws 172 (Fig. 8), by means of which the stationary molds may be accurately set to properly receive the movable molds.

105 The movable molds 154 are secured to 110 flange extensions of the rams 155 (see Figs. 3 and 31) by stud bolts 173 anchored in the molds and having freedom for limited sliding movement in the members 155, the extent of said limited sliding movement being 115 determined by adjusting nuts 174. The molds are each held forward, i. e., with the nuts 174 in contact with the ram 155, by four springs 175 (one of which is shown in Fig. 31), compressed between short lugs 176 120 of the molds and adjustable plugs 177 in the ram. The springs 175 thus further cushion the movable molds but their main purpose is to effect or permit of a perfectly uniform contact between the molds when they come together.

125 The movable molds 154, are provided with series of suitably distributed knock out pins. 178 (Fig. 30) having limited sliding actions through the molds, and which are held out- 130

wardly projected, by springs 179, in which positions their inner ends are flush with the matrix surfaces. The completed and cooled grid plates adhere to the molds 154, when the latter are withdrawn from the stationary molds, and, as the rams approach the end of their rearward strokes, the knock out pins 178 meet the head ends of a series of tap screws 180, adjustably secured in a rectangular frame 181 carried by the housing 87.

As the grid plates are thus freed from the open molds they drop down upon an inclined and curved chute 182 by which they are delivered to an endless apron or conveyor 183 carried by a frame 184 secured to the legs 35. The upper conveyor roller has a sprocket pinion 185 (Figs. 2, 5, 6, and 7), driven from a sprocket pinion 186, by a chain 187. The pinion 186 carries a worm gear 188 meshing with the worm 189 of a shaft 190, driven by the motor 127. Slack in the belt 183 may be taken up by set screws 191, and the proper taughtness in the chain 187 is had by moving the gear support block 192 on a rail 193, the shaft 190 being telescoped, as at 194, to permit such adjustment. The plates delivered by the chute 182 are carried up on the apron 183 until they deposit themselves, over the upper roll, upon a shelf 195. When this shelf has received a certain number of plates they may be temporarily piled upon a larger shelf 196 until they are to be carried away or delivered to the cutting or trimming machine.

The faces of the molds 153 and 154 are provided with the complementing intaglio or matrix surfaces which form the grids, and, as shown in Figs. 29 and 30, each pair of molds is capable of forming a plate of four grids, which plate is hardened in and delivered from the mold, after which it is cut apart and trimmed. The net work of horizontal and vertical grooves, 197 and 198, respectively, shown at the left in Fig. 29, form what are known as the wires and ribs of the completed grid, the surrounding channels 199 form the outer frames of the grids, and the pockets 200 form the terminal posts. Adjacent the outer channels 199 the molds are provided with relatively larger channels 201, which form heavy rods or bars at the ends of the grid plates, and which terminate, at their upper ends, in suitable air vents 202.

The middle, face portions of the molds are provided with hollow inserts 202, through which water is circulated from tubes or hoses 203, to keep the molds cool and to expedite hardening of the molded metal. These inserts are provided with complementing wedge shaped sections 204 which separate the incoming stream of metal. The upper ends of the inserts are flared out to form funnels for receiving the molten metal from the beaks or nozzles 59. As the lead is filled into the closed molds it quickly fills all the open spaces therein the displaced air being

discharged from the molds through the vents 202.

After each set of grid plates has been cast by and discharged from the molds it is necessary that the molds be smoked, or treated, before they are again closed to receive another charge of the molten lead. This I do by the mechanism illustrated particularly in Figs. 1, and 26 to 28, inclusive, and which may be described as follows: Upon the vertical end bars of the frame 181 I mount two bracket arms 205, which support a transversely extending guide bar 206. Upon this bar is slidably mounted a carriage or casting 207, through which extends and from which depends a burner tube 208 having two opposite rows of burner tips 209. The pipe or tube 208 has a valve 210, and connects with a flexible hose 211 that supplies gas to the burner 208 when the valve 210 is open. A pilot tube 212 connects with the gas supply, in advance of the valve 210, and has a burner tip 213, adjacent the lower end of the burner pipe 208, which, when once lit, will light the burner 208 each time the valve 210 is opened. When the lower burner tips 209 are thus ignited the flame immediately passes or runs up the pipe, lighting the other tips. The valve 210 is opened and closed by turning a hand rod 214, pivotally secured to the core extension bolt 215 of the valve. The bolt 215 is further provided with a finger 216, adapted to drop or swing into a notch 217, in the bar 206, when the carriage 207 is in the left hand position indicated by dotted lines in Fig. 26. When the finger 216 is in the notch 217 the valve 210 is closed and there is no gas flowing to the burner 208. In any other position of the finger 216, however, the gas supply to the burner is open and the latter is ignited.

The operation of the machine may be briefly described as follows: The motor 127 is not set in motion until after a sufficient amount of metal has first been melted up to the proper temperature in the pot 39. When this is done the feed mechanism is lowered into the pot, the operating rods 84 and 106 are connected up, a flow of water is started circulating in the pipes 203 and molds and current to the motor 127 is then turned on. With everything in readiness the clutch lever 131 is pulled back, thus imparting a continuous rotary motion to the sleeve 118 and the various cams carried by it. With the molds in closed positions, the plungers 57 move downwardly displacing a certain amount of metal that is then moved upwardly in the spouts 58 and fed down through the nozzles 59 to the molds. This feeding operation requires but a short time, and when completed a quick but short retraction of the plungers, by virtue of the rollers 88 passing from B to C, slightly draws the lead in the spout 58 back, to prevent dripping, before the valve mechanism shown in Fig. 18 operates to open the

valves 60. As soon as they are opened, however, the lead flows into the pump chambers as fast as the plunger lifts, whereupon the feed mechanism is in readiness for the next 5 succeeding mold filling operation.

The molds remain closed while the cam (167) surfaces from J to K remain in contact with the rollers 168, during which time the grid blades become hardened under the cooling 10 action of the water system. As the molds open the grid plates are kicked out and drop down upon the chute 182 from which they are carried up, by the conveyor 183, and deposited upon the shelf or support 195.

15 During the interval of time in which the molds are open, an attendant, stationed at the right side of the machine, grasps, turns, and pulls the handle bar 214, thus opening the valve 210, lighting the burner 208, releasing 20 the finger 216 of the carrier, and draws the burner 208 entirely through or across both sets of molds, causing the flames at the burner tips 209 to thoroughly and evenly treat or smoke all of the matrix surfaces.

25 He repeats this treatment by pushing the carrier back to its original position. It will be noted that as the gas cannot be turned off until the carrier is entirely returned the operator is warned by the light of the burner if he 30 has not so fully returned the carrier and consequently there is little danger of the burner being squeezed between the closing molds, which would be destructive to both the burner and the molds. In the event that the machine 35 does not function properly, it may be made to do so by regulating the various adjustments hereinbefore described.

It is understood that suitable modifications 40 may be made in the general design and structural details of the invention as herein shown, provided, however, that said modifications come within the spirit and scope of the appended claims. Having now therefore fully shown and described my invention, what I 45 claim to be new and desire to protect by Letters Patent is:

1. In a casting machine, a molten metal receptacle, molds, a mold operating mechanism, a feed mechanism for feeding molten metal 50 from the receptacle to the molds, and power transmitting means including a quick releasable connection operatively connecting the mold operating and feed mechanisms.

55 2. In a casting machine, molds, a molten metal receptacle, a feed mechanism adapted to feed the molten metal from the receptacle to the molds, power means for operating the feed mechanism, and means for automatically disconnecting the power means from the feed mechanism when the latter is subjected to more than a predetermined resistance.

60 3. In a casting machine, a mold unit, a molten metal feed chamber having a molten metal inlet, means for conveying metal from the chamber to the mold unit, a spring clos-

able valve for controlling the metal inlet to the chamber, means for periodically opening the valve, and means for effectively relieving the valve of contact or influence by the valve opening means during the time the valve is 70 closed.

4. In a casting machine, molds, a mold operating mechanism, a feed mechanism for supplying molten metal to the molds, and power transmitting means operatively connecting said mechanisms including an automatic release device for effectively disconnecting the said power transmitting means between said mechanisms with respect to each other when one of the mechanisms is 80 subjected to a normally excessive resistance.

5. In a casting machine, molds, a molten metal feed mechanism for supplying the molds with molten metal, a power device for operating the feed mechanism, and means including a spring retained release member, operative upon being subjected to a predetermined resistance of the feed mechanism for effectively disconnecting the power device therefrom. 85

6. In a casting machine, molds, a mold feed mechanism that is movable from its normal mold feeding position, a power element, and an operating mechanism connecting the feed mechanism with the power element, said operating mechanism including a manually operative device to effect a disconnection of the operating mechanism to permit the moving of the feed mechanism from its said normal operating position. 95

7. In a casting machine, molds, a molten metal feed pump to supply the molds, and a power transmitting mechanism for operating the pump, said mechanism including a yieldable connector adapted to automatically 105 effect a disconnection between the power mechanism and the feed pump when the latter is subjected to a predetermined or abnormal resistance.

8. In a casting machine, molds, a molten metal feed pump to supply the molds, and a power transmitting mechanism for operating the pump, said mechanism including a yieldable connector comprising two parts, and a friction member yieldably securing said 110 parts in operative relations. 115

9. In a casting machine, a molten metal feed pump, molds arranged to be supplied by the pump, and a power transmitting mechanism for operating the pump, said mechanism including a yieldable connector comprising two parts, a friction member retaining the parts in operative relations, and means for manually releasing the friction member. 120

10. In a casting machine, the combination including molds, a molten metal feed mechanism having a feed plunger and a valve associated therewith to supply the molds, power means for positively actuating the plunger 130

- and valve, and means including a yieldable connector for automatically disconnecting the power means from the feed mechanism when the latter offers abnormal resistance.
- 5 11. In a casting machine, the combination including molds, a molten metal feed mechanism having a feed plunger and a valve associated therewith to supply the molds, power devices for respectively operating the plunger and valve, and means for automatically disconnecting the power devices from the plunger and valve under predetermined circumstances.
12. In a casting machine, a molten metal chamber, a feed mechanism disposed over the chamber and mounted on a horizontal pivot so as to be swingable upwardly from the chamber, and a pair of simultaneously operative devices located one at each side of the machine for raising the feed mechanism on said pivot mounting.
- 15 13. In a casting machine, a molten metal chamber, a frame tiltably disposed with respect to the chamber and having its tilting axis at one end, a pump carried by the frame and normally submerged in the molten metal of the chamber, and means engageable with the frame near the end opposite from its tilting axis for tilting the frame to raise the pump above the level of the molten metal.
- 20 14. In a casting machine, a molten metal chamber, a frame tiltably disposed with respect to the chamber, a pump carried by the frame and normally submerged in the molten metal of the chamber, and a pair of laterally disposed lift screws arranged one at each side of the machine for tilting the frame to raise the pump from contact with the molten metal in the chamber.
- 25 15. In a casting machine, a molten metal chamber, a frame tiltably disposed with respect to the chamber, a pump carried by the frame and normally submerged in the molten metal of the chamber, a pair of rotatable screws operatively connected to the frame and adapted, upon being rotated, to tilt the frame and thereby raise the pump out of contact with the molten metal, and means for simultaneously rotating the screws whereby
- 30 50 they will operate in unison.
16. In a casting machine, a feed pump having a displacement piston, a cam acting member for reciprocating the piston, and a power transmitting mechanism connecting the cam acting member and piston, said mechanism being adjustable in part to effect a variance in the stroke length and displacement capacity of the piston.
- 35 17. In a casting machine having at least two sets of molds, a metal feed pump for each set of molds, each pump having a displacement piston, and power applying means comprising a cam actuated rod having connections at one end for the pistons including devices for selectively adjusting the stroke
- lengths and displacement capacities of the respective pistons.
18. In a casting machine, a pair of pumps having displacement pistons, a power device, means connected to the power device for reciprocating the pump pistons, means for simultaneously adjusting the stroke lengths of both pistons, and means, independent of the last named means, for adjusting the stroke lengths of both pump pistons with respect to each other.
- 70 19. In a casting machine, a pair of mold units in which the castings are formed, a chamber for containing molten metal, a feed mechanism for delivering charges of molten metal from the chamber to the respective mold units, and means for adjusting the feed mechanisms to regulate the charges of metal delivered to the respective mold units as to volume.
- 80 20. In a casting machine, a pair of mold units in which the castings are formed, a chamber for containing molten metal, a feed mechanism for delivering charges of molten metal from the chamber to the respective mold units, and means for adjusting the feed mechanism whereby the charges of molten metal delivered to both mold units may be simultaneously regulated as to volume.
- 85 21. In a casting machine, a pump having a reciprocable displacement piston, a rocker lever having one arm connected to the piston, a second rocker lever having one arm connected with the other arm of the first rocker lever, and power means for oscillating the second lever.
- 90 22. In a casting machine, a pump having a reciprocable displacement piston, a rocker lever having one arm connected to the piston, a second rocker lever having one arm connected with the other arm of the first rocker lever, and a continuously rotatable cam acting device for oscillating the second lever.
- 95 23. In a casting machine, a pump having a reciprocable displacement piston, a rocker lever having one arm connected to the piston, a power operated second lever, and a link connection between the first and second noted levers.
- 100 105 24. In a casting machine, a pump having a reciprocable displacement piston, a rocker lever having one arm connected to the piston, a power operated second lever, and a link connection between the first and second noted levers, said link connection being radially adjustable with respect to the fulcrum center of the second lever.
- 110 120 25. In a casting machine, a molten metal feed mechanism having a pump chamber with a displacement piston operative therein, a multipart power transmitting mechanism connected to the piston for reciprocating the same, and yieldable means acting upon the power transmitting mechanism to take up

slack in and prevent vibration between the parts thereof.

26. In a casting machine a pair of complementing molds, a ram for operating one of the molds, a feed mechanism for filling the molds, said feed mechanism having a piston and a rod for operating the piston, a rotor, means for continuously rotating the rotor, a cam carried by the rotor for actuating the ram, and a second cam carried by the rotor for actuating the piston rod.

27. In a casting machine a pair of complementing molds, a ram for operating one of the molds, a feed mechanism for filling the molds, said feed mechanism having a piston and a valve for controlling the feed of the molten metal to the molds, a continuously rotatable rotor, a cam carried by the rotor for actuating the ram, a second cam carried by the rotor for actuating the piston, and a third cam carried by the rotor for actuating the valve.

28. In a casting machine a pair of complementing molds, a ram for operating one of the molds, a feed mechanism for filling the molds, said feed mechanism having a piston and a valve for controlling the feed of the molten metal to the molds, a continuously rotatable rotor, and means operatively associated with the rotor for imparting predetermined co-related movements to the ram, piston, and valve.

29. In a casting machine a pair of complementing molds, a ram for operating one of the molds, a feed mechanism for filling the molds, said feed mechanism having a piston and a valve for controlling the feed of the molten metal to the molds, a continuously rotatable rotor, and lever acting members operatively connected to the rotor for imparting relatively timed reciprocating movements to the cam, the piston, and the valve.

In testimony whereof I affix my signature.
ARTHUR D. LUND.
